UNITED STATES PATENT OFFICE.

JAMES D. LAMONT, OF DETROIT, MICHIGAN, ASSIGNOR OF ONE-HALF TO ELLSWORTH S. BRYANT, OF DETROIT, MICHIGAN.

ELECTRIC COOKER.

993,178.

Specification of Letters Patent. Patented May 23, 1911.

Application filed June 13, 1910. Serial No. 566,474.

To all whom it may concern:

Be it known that I, JAMES D. LAMONT, a citizen of the United States, residing at Detroit, in the county of Wayne, State 5 of Michigan, have invented certain new and useful Improvements in Electric Cookers; and I do declare the following to be a full, clear, and exact description of the invention, such as will enable others skilled in 10 the art to which it appertains to make and use the same, reference being had to the accompanying drawings, and to the characters of reference marked thereon which form a part of this specification.

15 This invention relates to an electric stove and thermotic cooker, and consists in the construction and arrangement of parts hereinafter more fully set forth and pointed out particularly in the claims.

20 The objects of the invention are to provide a simple and efficient electric heater or stove and to place said stove in a case or cooking receptacle rendered non-conductive of heat wherein the heat generated by the 25 stove may be confined within a small area, provision being made for readily detaching the heater or stove from the receptacle or casing; for connecting and disconnecting the service or conductor wires thereto; for 30 insulating the electrical conductors to obviate the possibility of short-circuiting the current and to prevent the contact of moisture with any of the exposed contacts or electrically conductive parts.

35 The above objects are attained by the structure illustrated in the accompanying drawings, in which:—

Figure 1 is a central vertical section through a casing and heater or stove made 40 in accordance with my invention, showing a cooking vessel in place upon the heater within the casing or receptacle. Fig. 2 is a horizontal section as on line 2—2 of Fig. 1. Fig. 3 is an elevation of the socket plate into 45 which the ends of the conductors of the resistance coils extend to form contact pins. Fig. 4 is a sectional view as on line 4—4 of Fig. 3. Fig. 5 is a fragmentary view in section through the socket plate and neck of 50 the heater, said parts being separated.

The case or receptacle in which the heater is located and in which the cooking is done is preferably cylindrical in shape and is composed of an outer wall 1 and an inner 55 wall 2, said walls being spaced from each

other and the space between them being filled with mineral wool 3 or other like material which is non-conductive of heat. Within the central portion of the case is a cylindrical chamber 4 closed at the top by 60 a removable cover 5 which is fitted into the outer opening of said chamber in a manner to make a tight closure, the top of the case proper being closed by a supplementary cover 6.

65 The stove or heater wherein the heat for cooking is generated, consists of a hollow circular body portion 7 closed by a removable bottom 8 having feet 9 which elevate the bottom of the heater from the bottom of the chamber 4. The heater or stove is preferably cast from suitable metal and formed integral therewith and projecting laterally therefrom is a hollow, tapered neck portion 10. Within the hollow heater is a 70 suitable resistance coil 11. From the terminals of the coil 11 extend the contact pins 12 and 13, respectively, which pass through and are embedded in a filling of plaster of Paris or like non-conductive material 14 75 contained within the hollow neck 10 of the heater, the ends of said pins projecting through the hollow tenons 10^a extending beyond the terminal of the neck portion, as clearly shown in Figs. 3 and 4.

80 Formed through the wall of the case and communicating with the central chamber 4 thereof near the bottom, is an opening in which is seated a bushing 15 of lead or other material of poor conductivity. The inner portion of the bushing 15 is tapered to receive the neck 10 of the heater which coincides therewith and is adapted to fit therein. Fitted into the outer portion of said bushing which is also made tapering, is a tapered 85 socket plate 16. The tenons 10^a of the neck of the heater extend through the registering apertures 17 in the bottom of the socket plate 16 and said parts are securely fastened together by means of a screw 19 which passes through the bottom of the socket plate into a tapped center piece 20 of the neck which crosses between and connects the sides thereof. By this arrangement, the neck of the heater and the socket plate 16 may be 90 securely fastened together in a manner to enable said parts to be readily disengaged, when desired. The outer ends of the contact pins 12 and 13 lie within the socket plate in position to receive the plugs 21 and 95 100 105 110

22 carrying the service conductors 23 and 24, said plugs having therein the usual contact plates with which said conductors are connected and which make contact with the 5 ends of said pins when placed thereon, thereby effecting a continuity of the electric circuit through the resistance coil 11 in the heater.

It will be noted that the arrangement is 10 such as to prevent moisture within the chamber 4 coming in contact with the terminal pins of the resistance coil, or with the conductors in a manner to effect a short circuiting thereof. It will also be noted that the 15 electrical conductors are so insulated as to prevent a grounding of the current on any of the metal parts of the case.

By employing the individual plugs 21 and 22 to connect the service wires 23 and 24 20 with the terminal pins of the resistance coil, any lateral straining of said pins is avoided, thereby obviating the possibility of breaking away the insulating material from around said pins and insuring always a ready 25 and easy connection of the service wires with the terminals of the resistance coil of the heater. It will also be observed that by removing the screw 19 which connects the socket plate with the neck of the heater, said 30 heater may be readily removed from the chamber 4 of the case for the purpose of cleaning it or for making repairs thereto, when necessary. By inclosing the heater within a chamber whose wall is spaced from 35 the outer wall of the case by a filling of non-conductive material, the heat which is generated by the heater is prevented from radiating and is retained within said chamber, enabling the electric current which generates 40 the heat within the heater to be turned off after the temperature of said chamber has been raised to the required degree, the retained heat completing the operation of cooking the food within the vessel 25 which 45 rests upon the heater within said chamber, without requiring the consumption of additional current. As the heat cannot escape from the chamber 4 by radiation or conduction, a very high temperature may be re- 50 tained in said chamber for many hours after the heating current has been turned off, enabling the operation of cooking to be accomplished in a very inexpensive manner.

Having thus fully set forth my invention,

what I claim as new and desire to secure by 55 Letters Patent, is:—

1. A cooking apparatus having a central cooking chamber provided with an opening in the wall thereof, a bushing of insulating material fitted into said opening a heater 60 within said chamber detached therefrom, a resistance coil within said heater having terminal contacts, the terminal contacts of said coil passing through said bushing in the wall of the chamber and insulated therefrom, and means for detachably connecting the service wires with the projecting terminals of said coil. 65

2. A cooking apparatus comprising a receptacle having a central cooking chamber, 70 said chamber having a tapered opening in the side thereof, a heater in said chamber, said heater having an integral tapered neck portion projecting laterally therefrom and insertible into said opening in the side of 75 said chamber from within to render the heater removable from said chamber, a resistance coil within said heater, conductors leading from the terminals of said coil and passing through the neck of the heater, insulating material within the neck of the heater around said conductors, and means for connecting the service wires with the terminals of said coil wholly within the wall of said chamber. 80

3. A cooking apparatus, comprising a case having a cooking chamber therein, a hollow burner in said chamber, a resistance coil within said burner, the wall of the burner having a laterally extending neck, the wall of the case 90 having an opening to receive the neck of the burner, a filling of insulating material within said neck, conductor terminals from said coil passing through and embedded in said filling of insulating material, a socket plate 95 within the outer end of the opening through the case receiving the end of the neck of the burner, the contact terminals of the coil lying within the socket plate, and means for detachably connecting the service wires with 100 said terminals.

In testimony whereof, I sign this specification in the presence of two witnesses.

JAMES D. LAMONT.
